REFRIGERATING APPARATUS AND METHOD

Paul A. Bancel, Montclair, N. J., and John Kirgan, Easton, Pa., assignors to Ingersoll-Rand Company, Jersey City, N. J., a corporation of New Jersey

Continuation of application Serial No. 716,938, March 23, 1934. This application filed November 25, 1938. Serial No. 242,230

16 Claims. (Cl. 62—152)

This invention is a continuation of our application Serial No. 716,938 filed March 23, 1934, and relates to improvements in refrigerating apparatus, and especially to refrigerating apparatus, and a method of refrigeration in which the vaporization of a portion of a liquid refrigerant reduces the temperature of said refrigerant to the extent required.

An object of our invention is to provide refrigerating apparatus of the kind mentioned, with an evaporator including a plurality of compartments or chambers, each equipped with an evacuator to carry away the vaporized portion of the refrigerating medium, and suitable connections for controlling said apparatus, and enabling it to be adjusted to meet the requirements of a heavier or a lighter load, in a practical, efficient and economical manner.

With refrigerating systems using a non-volatile substance such as water as the refrigerating or cooling medium, an evaporator in the form of a container for water to be chilled is employed. The pressure in this evaporator is lowered to such a point that when water is admitted thereto at a given temperature, some of the water is immediately vaporized. Thus a body or mass of water in the evaporator can be cooled to the necessary degree and utilized as needed. But the water vapor obtained from vaporization of part of the water must be removed from the evaporator, and this removal may be effected by a steam ejector, which carries the vapor to a condenser wherein the discharge of the ejector is liquefied. Such a system with a single evaporator chamber and a single ejector will serve quite well at approximately fixed or predetermined loads, but it is quite unsuitable for operation when the load varies. Therefore, if such a system is built for a rated load it cannot be operated advantageously to give a reduced output, and if it is constructed for a small load the output cannot greatly be increased. The cause of this is the fact that the capacity of the steam ejector or steam jet booster, that is, the pounds

of water vapor evacuated thereby in a given time at fixed suction pressure determined by the pressure in the evaporator itself, is substantially constant, regardless of the amount of steam being used. Furthermore, the steam ejector is substantially a constant volume compressor and because of the peculiar characteristics of water vapor which cause the specific volume to increase as the vapor pressure and density decrease, at reduced loads when the evaporator

temperature and vapor pressure therein have decreased the volume of vapor formed in a given time is substantially the same and the same rate of steam flow to the ejector is still required. Yet another characteristic of the steam jet booster is that its steam flow must be maintained at the rated value so long as the relation between the suction pressure (or chilled water temperature) in the evaporator and the discharge or condenser pressure remains constant. Hence this type of steam jet may become less and less economical to operate as the load thereon falls, and it must be turned on completely, using its full rated steam consumption, or completely off and rendered inoperative, so long as the aforementioned conditions of pressure and volume remain at substantially normal and constant values. But if a refrigerating system of this character is equipped with several evaporator chambers and steam ejectors, connected in multiple and adapted to work with either all of its evaporator chambers and ejectors, or less than all of said chambers and ejectors in operation, the load can be varied within quite widely separated limits, and steam is saved at varying loads, because the consumption or expenditure of power can thus always be adjusted to actual operating conditions.

This invention is particularly designed to include a plurality of chambers for evaporating and cooling water and an evacuator, such as a steam ejector, for each chamber, and means for allowing selective operation of one or more of said chambers. A further object thereof is to provide refrigerating apparatus having multiple evaporator chambers and means which can be readily actuated to put all or less than all of the chambers at work as conditions demand.

Another object is to provide refrigerating apparatus which includes an evaporator having several chambers, each with its own evacuating means arranged so that the vaporized portion of the refrigerant can be delivered to an ordinary condenser. Thus we avoid a condenser of special and costly design, such as a condenser having several chambers, with separate connections for same.

All the objects and advantages of the invention are indicated in the following description, taken with the drawing showing a preferred form, but the disclosure is for the purpose of illustration only, and many changes can be made without going beyond the principle or scope of the invention herein set forth.

In the drawing

Figure 1 shows refrigerating apparatus, partly in section, according to the invention,

Figure 2 is a section on line 2—2 of Figure 1; 5 and

Figure 3 is a section on line 3—3 of Figure 1.

The numeral 1 is employed to indicate a water evaporator of any desired size or shape which contains a number of sections or compartments, 10 three for example, indicated at 2, 3 and 4, formed between inside partitions 5 and the ends 6.

A water supply pipe or conduit is indicated at 7, with branches 8 leading to each of the aforesaid chambers or compartments. The 15 branches terminate within said chambers in nozzles or sprayers 9, each of sufficient capacity. The pressure within any chamber of the evaporator 1 that is working will, of course, be low enough so that when water is admitted some of 20 it will be vaporized at once and the remainder cooled to the required extent. If the temperature of the incoming water is 50° F., for instance, the system can be so designed and the pressure in the evaporator so reduced that the vaporization 25 of a small part of the water admitted will cause the entire mass of incoming water, when all three chambers are in operation, for example, to be cooled down to 47° F. In the branch pipes 8 are admission and cut-off valves 10 so that one or more of the nozzles can be shut off whenever desired.

To carry off the water thus chilled, we provide a common delivery means or conduit 11 connected by branches 12 with valves 13 therein to the 35 separate compartments of the evaporator 1. To these branches the chambers discharge through outlets in the bottom.

For removal of the water vapor created by vaporization in the chambers of the evaporator, 40 steam ejectors or evacuators 14, in the form of L-shaped tubular members which communicate at one end with the inside of the chambers of the evaporator through openings 15 in the top, and are connected at their opposite ends to a 45 common discharge conduit 16 which leads to a suitable condenser, are used. The ejectors receive steam nozzles 17 which are connected by pipes 18 to a common steam supply line 19, and these branch pipes 17 each carry an admission 50 and shut-off valve shown at 20. The ejectors not only remove the water vapor, but maintain 55 the necessary vacuum to vaporize some of the water in any chamber that is in operation.

With this arrangement any number of chambers 55 in the evaporator from one up to the total can be put into operation, or conversely rendered inoperative, as may be necessary.

If all are to work at once, the valves 10 are all opened to admit water to the three chambers 60 of the evaporator, and all of the steam ejectors 14 are employed to carry away the water vapor to the condenser (not shown) by opening the valves 20. These ejectors compress the water vapor to the pressure in the condenser, and 65 therefore are sometimes called thermo-compressors. The chilled water is withdrawn through the delivery pipe 11 with all valves 13 open. To cut out one or more chambers, the valves 10, 13 and 20 thereof are shut.

70 The drawing illustrates the chamber 4 as being out of service. In this chamber the level of the water may be maintained the same as the water level in the other two chambers. Any water trapped in the chamber 4, of course, can 75 not flow out through the branch 12. The trap-

ping of water in an inactive chamber, such as 4, is not a necessity and the only reason that it is done occasionally is to reduce the quantity of water circulating in the system and thereby avoiding flooding of the active chambers. The 5 pressure in this chamber 4 may be slightly higher, that is to say, the vacuum therein is less because the steam jet thereof is not active and the pressure inside this compartment is therefore equal to the pressure in the condenser. Hence no 10 vaporization takes place in chamber 4 but in the other two chambers a part of the water is vaporized as soon as it enters and the water is exhausted through conduit 16. The chilled 15 water is carried away as before by the conduit 11.

With this construction the system can be operated under a wide range of conditions of varying load without waste of steam or power. In this type of refrigerating apparatus the capacity of a given steam ejector, that is, the number 20 of pounds of water vapor drawn by the ejector from any chamber through the member 14 and compressed at a fixed suction pressure, which is the pressure in the chamber above the cooled water therein, is approximately constant, re- 25 gardless of the amount of steam used. Hence the amount of refrigeration in each chamber, or the quantity of heat removed from any chamber, is also, under the same conditions, approximately constant regardless of the amount of 30 water which flows through each chamber. That is, if the mass of water passing through any chamber is large, the temperature reduction is less than it will be if the mass of water is small, because the quantity of water vapor evacuated 35 by the steam jet is the same and therefore the quantity of heat extracted from the water does not appreciably vary. Reference is here made to a booster which is operated with steam at approximately constant pressure and not to a 40 series of ejectors designed for different pressures and steam flows. Therefore, to save steam under varying load conditions the evaporator is made with several chambers to serve as multiple units and the necessary control is provided by suitable 45 means, such as branch pipes and the valves 10, 13 and 20. Automatic regulation, of course, may also be practiced.

Preferably the quantity of water flowing 50 through the pipe 7 to the evaporator is varied according to the amount of refrigerating effect 55 needed at the place to which the chilled water is conducted. If all the chambers 2, 3 and 4 are working and the maximum amount of water is supplied thereto by the pipe 7, the chilled water leaving the evaporator may be at 47° F. At the place of use it may be all warmed up once more to 50°, in which case the maximum amount is again supplied to the evaporator 1 and all three 60 chambers are used to cool it again to 47°. If, however, less refrigeration is needed the water may be so regulated that only two-thirds of the maximum runs through the pipe 7 to the evaporator. In that event only two of the chambers need be used, and, as the amount of vapor re- 65 moved is the same as previously in each of these, the reduced quantity of water will be chilled to 47° as before. Further, if the load is again decreased the water can be regulated as before so that only one-third of the maximum quantity 70 runs through the pipe 7, and two of the chambers will now be put out of operation. In this instance the chamber which is working will cool the smaller volume of water which passes through it to such an extent that it is again 75

supplied through the delivery conduit 11 at a temperature of 47°.

The reduction of the water returned to the evaporator through the pipe 7 in this way can be accomplished by any suitable appliance to regulate the quantity which is to be chilled in the evaporator 1.

On the other hand the apparatus will operate just as effectively with a given quantity of water which is neither increased nor decreased as it flows from the header 11 to the place of use and back to the supply line 7. Assume the water is chilled from 50° to 47° in the evaporator 1 with all chambers working. The water may again re-absorb enough heat at the place to which it is conducted by the conduit 11, and where the refrigerating effect is desired, to raise its temperature to 50°. When the water is returned to the evaporator 1 it must of course be cooled by passing it through all three of the compartments 2, 3 and 4. If, however, the same quantity is warmed only 2° so that the return temperature is 49°, then two of the chambers are sufficient to chill the same mass of water down to 47°. Again, if this given quantity of water is warmed up to only 48° at the place mentioned, one chamber is enough to cool it when it once more returns to the evaporator 1. In any case each of the pipes 8 and valves 10 are made large enough to transmit all of the water supplied through the conduit 7, but the amount of water vapor which can be removed from each chamber by the ejector thereof is always the same, regardless of the amount of water admitted thereto.

The branches 12 must also be large enough so that each can carry off from any chamber the maximum of the water supplied by the conduit 7.

In connection with the above described modes of operation, it should be remembered that each steam ejector will extract water vapor from each chamber at a constant rate, and therefore remove heat from the water itself at a constant rate only so long as the other factors heretofore mentioned are controlled in the described manner to produce an absolute pressure in the chambers which does not vary. This pressure must be relatively low in order to enable part of the incoming water to be vaporized upon entrance. If the temperature of the inflowing water drops below its normal full load value, the vaporization will be decreased, enabling the ejectors to reduce the absolute pressure in each chamber above the level of the chilled water therein. This lower absolute pressure will result in a lower chilled water temperature. Such a drop in absolute pressure in the chambers 2, 3 and 4 may take place, for instance, if the water is supplied through the pipe 7 thereto at a temperature lower than before, as when the apparatus is running at a given capacity, and the load is decreased without altering or reducing the number of chambers in operation. In that case the pressure in the chambers will drop as above stated, and the chilled water will be cooled to a temperature lower than desired. But this drop in pressure can be avoided by cutting out one or more chambers, and thereby maintaining the absolute pressure substantially constant in the remaining chambers.

In practice the apparatus must always be operated with the controlling valves, especially the valves 10, in fully open or fully closed position, so that each chamber is either in full operation, or completely cut out.

From the foregoing description it will be seen that operation of the evaporator chambers can

be selectively controlled by the means consisting of the water supply pipe 1 and delivery pipe 11, with the branch connections with the valves therein leading to the various chambers, and the branched steam supply lines with the valves 5 therein, and no more steam is consumed than is necessitated by the load at any particular time.

Another important advantage is that, with the evaporator divided into separate chambers, all of the steam ejectors can be arranged to deliver 10 into the single discharge means or conduit 16 by which the water vapor and steam is conveyed to the condenser, and this condenser can be a condenser with a single chamber, because the multiple chambers on the interior of the evaporator 15 1 and the use of the branched inlet and discharge conduits make a condenser with a number of chambers unnecessary. Likewise there is no necessity for cut-out valves in the various 20 evacuator casings 14. Of course the conduit 16 may be omitted, and the ejectors can then be connected to the condenser directly.

We claim:

1. Refrigerating apparatus having multiple chambers wherein a refrigerant is cooled, evacuator members for said chambers, refrigerant supply and delivery members for said chambers, the supply members being united and the delivery members being united, and means for selectively controlling the said members for rendering any chamber inactive at any instant and thereby selectively controlling the operation of said chambers.

2. Refrigerating apparatus having chambers for receiving a liquid refrigerant, a portion of which is to be vaporized therein, means common to all of the chambers for supplying liquid refrigerant thereto, means common to all of the chambers for discharging liquid refrigerant therefrom, an evacuator for each of said chambers, the evacuators acting to maintain a substantially equal vacuum in said chambers and to remove vapor therefrom, discharge means common to all of said evacuators to enable the latter to be connected to a single condensing chamber and to produce the same back pressure on all evacuators, and means for selectively controlling both said common means and the evacuator for any chamber to selectively render any chamber inactive at any instant.

3. Refrigerating apparatus comprising multiple chambers wherein a refrigerant is cooled, a common supply pipe for refrigerant having branches connected to each of said chambers, common delivery means for refrigerant having branches connected to each of said chambers, means to selectively control the flow of refrigerant through the branches connected to the chambers and stop the flow of refrigerant through any branch at any instant, and a selectively operable evacuator for each chamber for removing vapor from active chambers to selectively control the operation of the chambers and render any chamber inactive at any instant, said evacuators being connected to maintain a substantially equal vacuum in all of the active chambers.

4. Refrigerating apparatus comprising chambers wherein a liquid refrigerant is cooled, means for selectively controlling the operation of said chambers and for rendering any chamber inactive at any instant including a supply pipe for refrigerant connected to each chamber, a delivery pipe for refrigerant having branches independently connected to each chamber, each branch being of substantially the same capacity as the 75

- said delivery pipe, and selectively operable evacuators connected one to each chamber to remove vaporized refrigerant from the active chambers, the evacuators being connected to maintain a substantially equal vacuum in all of the active chambers.
5. The method of producing and controlling refrigeration consisting in admitting refrigerant to a plurality of chambers, extracting heat from the refrigerant in each of said chambers at a given pressure therein, and varying the number of chambers in operation to maintain the pressure and the quantity of heat thus extracted substantially constant in each active chamber by rendering any chamber inactive at any instant.
10. The method of producing and controlling refrigeration which consists in admitting a liquid refrigerant to a plurality of chambers, extracting heat from the refrigerant by vaporizing a portion thereof in the chambers, maintaining substantially the same vaporization in all the chambers, and varying the number of chambers in operation by rendering any chamber inactive at any instant to maintain said pressure and the quantity of heat extracted in an active chamber substantially constant.
15. The method of producing and controlling refrigeration consisting in dividing a liquid refrigerant into separate masses, vaporizing a portion of each mass to cool the remainder thereof, removing the vaporized portion, combining the cooled masses for utilization, and varying the number of separate masses by stopping vaporization of any mass at any instant to regulate the amount of refrigeration capable of being effected by the combined masses.
20. Refrigerating apparatus having a plurality of chambers for the evaporation of a refrigerant, independent evacuating means for each chamber, means common to all the chambers for admitting refrigerant to each chamber, means common to all the chambers for delivering the refrigerant from the chambers, and means for selectively rendering any chamber inactive at any instant, and a conduit connected to said independent evacuating means and arranged for subjecting such a chamber to the discharge pressure of the evacuating means of an active chamber.
25. The method of producing and controlling refrigeration consisting in treating a liquid refrigerant in separate masses by vaporizing a portion of each of said masses, removing and compressing said portions, selectively stopping the vaporization of any one of said masses at any instant and subjecting it to the increased pressure of the vaporized portion of another of said masses.
30. Refrigerating apparatus having multiple chambers wherein a refrigerant is cooled, an evacuator member for each chamber, common refrigerant supply and delivery members for said chambers, and means to render inoperative the members associated with each one of said chambers thereby varying the combined capacity of the chambers by rendering any chamber inactive at any instant.
35. Refrigerating apparatus comprising a plurality of evaporator chambers wherein a liquid refrigerant is chilled by evaporation of a portion thereof, means common to all the chambers to distribute refrigerant thereto, means common to all the chambers to withdraw refrigerant therefrom, individual means to remove vaporized refrigerant from each chamber and discharge the same into a common condenser, and means associated with each one of the chambers to suspend refrigeration therein at any instant.
40. Refrigerating apparatus comprising a plurality of evaporator chambers wherein a liquid refrigerant is chilled by evaporation of a portion thereof, means common to all the chambers to distribute refrigerant thereto, means common to all the chambers to withdraw refrigerant from the chambers, individual means to remove vaporized refrigerant from each chamber, means to discharge the same into a common condenser, and means associated with each chamber to transfer its refrigerating load to the remainder of the chambers at any instant.
45. The method of cooling a liquid refrigerating medium which consists of dividing said medium into masses, removing heat from each mass by evaporating a part thereof, combining the treated masses for utilization thereof, and controlling the total refrigerating effect by varying the number of masses into which the refrigerant is divided by stopping evaporation of any mass at any instant.
50. The method of cooling a liquid refrigerating medium which consists of dividing said medium into masses, removing heat from each mass at a substantially uniform rate by evaporating a portion thereof, and varying the number of masses into which the refrigerant is divided according to the total amount of cooling required by stopping evaporation of any mass at any instant.
55. In vapor jet apparatus for providing a supply of cooled liquid, the combination of a plurality of evaporating chambers, an ejector connected to each chamber for withdrawing vapor therefrom to effect cooling of liquid therein by partial evaporation, and means for circulating liquid selectively through several evaporating chambers or through a smaller number of said chambers and to render any chamber inactive at any instant to provide said supply of cooled liquid.
60. In a refrigerating apparatus, an evaporator having at least two chambers therein to chill refrigerant, a refrigerant supply conduit for the evaporator, a supply valve for each chamber to selectively control at any instant the flow of refrigerant from the supply conduit to each chamber, a refrigerant discharge conduit for the evaporator, a discharge valve for each chamber to selectively control at any instant the flow of refrigerant from each chamber to the supply conduit, a common steam header for the evaporator, a steam evacuator for each chamber to vaporize and chill the refrigerant, and a steam valve to control the flow of steam to each evaporator from the header and thereby regulate the degree of refrigerant vaporization in the respective chambers, whereby any chamber may be selectively rendered inactive at any instant.
